Primary Examiner — Lauren R Calve

(57) **CLAIM**

The ornamental design for a food and beverage container with dispensing function, as shown and described.

DESCRIPTION

1. Food and beverage container with dispensing function

1.1 : Front

1.2 : Left

1.3 : Back

1.4 : Top

1.5 : Bottom

1.6 : Perspective

1.7 : Perspective view in alternate position

1.8 : Exploded view in a smaller scale

The broken lines shown represent portions of the food and beverage container with dispensing function that form no part of the claimed design; the right side view is not shown because it is a mirror image of the left side view; the irregular dashed lines represent contours, shading, and transparency, and do not illustrate surface ornamentation or decoration; reproduction 1.7 is a perspective view shown in an alternate position; the bracket shown in reproduction 1.8 clarifies that the articles in the exploded view comprise a single inventive claim.
